UNITED STATES PATENT OFFICE.

ALONZO B. ELY, OF GROTON, NEW YORK, ASSIGNOR TO CORONA TYPEWRITER COMPANY, INC., OF GROTON, NEW YORK, A CORPORATION OF NEW YORK.

TYPEWRITING-MACHINE.

1,398,322.

Specification of Letters Patent. Patented Nov. 29, 1921.

Application filed March 20, 1919. Serial No. 283,703.

To all whom it may concern:

Be it known that I, ALONZO B. ELY, a citizen of the United States of America, and a resident of Groton, county of Tompkins, 5 and State of New York, have invented certain new and useful Improvements in Type-writing-Machines, of which the following is a full and clear specification.

The object of this invention is to provide 10 a typewriting machine with a simple and efficient dead-key action, the principal feature of which is to so construct the mechanism that only lower-case characters will be dead, so that when the machine is adjusted 15 for middle-case characters as well as upper-case characters all the type will be alive, thereby increasing the capacity of the machine to the extent of two characters on each dead type-lever, as more fully hereinafter 20 set forth.

In the drawings—

Figure 1 is a perspective view of the parts 25 of a typewriting machine needed to illustrate one way of applying my invention; Fig. 2 is a perspective view in detail of a device for holding the rock-shaft in normal position;

Fig. 3 is a detail front elevation showing 30 the position of the parts when adjusted for upper-case printing.

I have illustrated the present embodiment 35 of the invention as adapted to a machine such as shown in Rose Reissue 13,935, dated June 22, 1915, but it will be understood that 40 the invention is susceptible of application to other types of typewriting machines. In this type of machine, the escapement-lever 5 is operated by a tappet 6 carried by a bail 7 pivotally mounted at its lower end on a transverse rod 8 which is mounted in the 45 lower ends of vertical posts 9. The bail is adapted to be swung rearwardly whenever a character-lever or space-lever is operated, to thus cause the tappet 6 to give a feed movement to the escapement lever 5. The 50 posts 9 support at their upper ends the frame-members 10 and these frame-members support the usual carriage-bed 11, so that to obtain case-shift it is simply necessary to

raise the posts 9 to thereby elevate the frame-bars 10 and the carriage supported upon the bed 11. This case-shifting of the carriage-supporting-frame will also shift the bail 7, so that the feed-operating tappet 6 is always in position to cause a feeding operation to take place, irrespective of case-shift. The bail 7 is shifted through the medium of the usual universal-bar 12 which is connected at its ends by links 13 to bell-cranks 14, the forwardly-extending arms of each of the bell-cranks being connected by a transverse rod 15 which engages vertical slots 16 in the vertical arms of the bail, said universal-bar being in position to be operated in the usual manner by the spacing-lever 17 or one of the 60 key-levers 18. The key-levers 18 are connected as usual to the type-bars 19, and these type-bars are pivotally mounted in the usual segment 20 fastened to the rear wall of the machine-frame. The case-shift levers (one 65 of which is shown at 21) are operatively connected to a transverse shaft 22 and this shaft is connected by arms 23 to the lower ends of the posts 9. These case-shifting devices are adapted to be held up or locked in 70 their adjusted positions by any suitable means, not shown.

To apply my present invention to the type 75 of machine above described, I pivot the tappet 6 at 24 to the upper side of the bail and provide a light coil-spring 25 to normally hold this tappet against an upstanding stop 26 carried by the top bar of the bail, so that said tappet is free to be swung laterally away from said stop 26. I slidingly mount 80 on the rear wall of the machine-frame an upright bar 27 whose upper end is beveled off at 28, this bar being so positioned that when it is elevated said inclined edge 28 will impinge against the left-hand edge of tappet 6 and shift the same laterally out of the path of the escapement-lever or dog and hold it in such position during the backward swing of the bail, so as to thereby permit the bail to have its full backward swing 85 without operating the escapement. It will be understood, of course, that the bail or other part of the mechanism is connected to 90 95

the usual ribbon-vibrating devices so that, even when the tappet 6 is adjusted to non-feeding position, the ribbon mechanism will nevertheless receive its usual vibratory operation.

I provide suitable mechanism for elevating the bar 27 every time a dead key is operated, so that the feeding of the carriage will be avoided when a dead key is operated.

- 10 I prefer for this purpose a rock-shaft 29 journaled in a pair of bearings 30 fastened to the rear wall of the machine-frame and in a third bearing 31 fastened to the supporting lug 32 at one end of the segment.
- 15 One end of this rock-shaft is bent forwardly so as to form an arm 33 which extends through a vertical slot 34 in a depending part 35 formed on the forwardly-projecting lower end of the bar 27, so that when the 20 rock-shaft is rotated to lift the arm 33, said bar 27 will be likewise elevated.

To operate the rock-shaft 29, I bend that part of the shaft between the outer end of the bearings 30 and the end-bearing 31 so as 25 to form a forwardly-extending part 36 which lies just above the type-bar slots in the segment and is curved to approximately conform to the arcuate curvature of the segment. This curved member 36 lies in the path 30 of one or more of the type-bars. I preferably make this part 36 long enough to be operated by any one of four or five type-bars, and those type-bars that are intended to operate this member 36 I provide with a cam 35 or toe 37, whose curved face, when the type-bar is thrown upwardly to printing position, strikes against the curved member 36 and imparts a forwardly rocking action to the shaft 29, to thus raise the bar 27 and put the 40 tappet 6 out of commission. The rock-shaft is bent upwardly and downwardly at its outer end at 38, so as to avoid contact with the end of the segment when the shaft is rocked, it being, of course, necessary that 45 the bearings 30 and 31 shall be in axial alignment. The rock-shaft is held in its normal position with the bar 27 in its down position by a light coil-spring 39 which is connected at its upper end to the forwardly-extending end 40 of the rock-shaft and at its 50 lower end to rearwardly-extending lug 41 formed integral with a bracket 42 which in turn is formed integral with the outer bearing 31, said bracket 42 being also provided 55 with an upstanding lug 43 which serves as a stop for the shaft extension 40 to thus hold the parts in their proper position for operation by the type-bars.

It will thus be seen that upon the operation of one of the dead keys, its type-bar 19 will cause the rock-shaft to elevate the bar 27 and thus force the tappet 6 laterally to an inoperative position. This operation will take place during the backward swing of the

bail 7, but before the tappet 6 reaches the 65 escapement-lever or dog, so that feeding of the carriage will be avoided when one of these dead type-bars is operated. The lower-case characters of the dead type-bars are, as usual, underscores, accents and any other 70 character where a printing operation is desired without a carriage-feeding operation. With this invention, it will be observed that when the carriage-bed is shifted upwardly to middle-case or upper-case position, the tappet 75 6 is thereby elevated, as shown in Fig. 3, to a position out of reach of the bar 27, so that when thus shifted for middle-case and upper-case printing the operation of one of the dead keys, while it will operate the rock-shaft and elevate the bar 27, will not prevent feeding of the carriage in the usual manner; this enables me, as is obvious, to utilize the type-heads of the dead type-bars 80 to carry middle-case and upper-case characters, thereby increasing the capacity of the machine to the extent of two characters for each dead key. In other words, my invention permits each dead-key action to be transformed into a live-key action when the 85 machine is adjusted for printing middle-case or upper-case characters.

It will also be observed that a feature of importance lies in the fact that by employing a rock-shaft in position to be operated 90 by the type-bars, I may so construct the devices that they will be adapted to the use of a plurality of dead keys without specially designing the machine for that purpose, it being simply necessary to locate the dead 95 type-bars in the segment in such position that their cams or toes 37 will cause an operation of the rock-shaft; and this capacity of the machine to increase the number of dead type-bars at will is particularly advantageous in a machine where, as in my invention, the case-shifting transforms the dead type-bars, into live type-bars, since by this scheme the addition of a dead key to the machine for a lower-case character does not 100 105 destroy the use of that key for middle and upper-case characters.

In dead-key action, the problem is always as to how to obtain a full throw of the ribbon-vibrating lever of the carrier to printing position without feeding the carriage. My present construction lends itself nicely to the solving of this problem, since the member (bail 7) which operates the ribbon-vibrating mechanism receives a full actuation even with a dead-type action, so that the ribbon-vibrator will be completely operated irrespective of whether a live-key action or a dead-key action is operated. The ribbon-vibrator may be operated from the swinging bail 7 in any suitable manner, one way of doing this being illustrated in Petermann Patent 1,121,044, dated December 15, 1914.

- In the drawing, I have illustrated the ribbon-vibrating lever in dotted lines at 45 and the means for vibrating this arm at 46, this latter means being connected to the bail 7 5 in the usual manner.
- The nature and scope of the invention having been thus indicated and its preferred embodiment having been specifically described, what is claimed as new is:
- 10 1. In a typewriting machine, the combination of character keys, a member operable by each key for actuating an escapement and a ribbon vibrator, type bars operable by said keys, and means operable directly by one or 15 more of the type bars for preventing operation of the escapement when said member is operated.
2. In a typewriting machine, the combination of case shift mechanism, character keys, a member operable by each key for actuating an escapement and a ribbon vibrator, type bars operable by said keys, and means operable by one or more of the type bars for preventing operation of the escapement when 25 said member is operated, said case shift mechanism being operatively connected to impart a relative movement between said member and said type-bar-operated means into and out of coöperation relation with 30 each other.
3. In a typewriting machine, the combination of character keys, type bars operable by said keys, a vibrating member operable by each key, an escapement-operating tappet 35 pivotally mounted on said member, and means operable directly by one or more of said type bars for shifting the tappet about its pivot out of operative position.
4. In a typewriting machine having an 40 escapement and ribbon vibrator and a case-shift frame, the combination of character keys, a vibrating member operable by each key operatively connected to actuate the ribbon vibrator, a tappet pivotally supported 45 on said member, means for normally holding said tappet in coöoperative relation with the escapement, type bars operable by the keys, means operable by one or more of said type bars for swinging the tappet about its pivot 50 out of coöoperative relation with the escapement, and connections between the shift frame and said vibrating member for moving said member and tappet with the escapement out of coöoperative relation with the 55 tappet-swinging means.
5. In a typewriting machine having a platen carriage, carriage-feeding mechanism, and case-shift mechanism for elevating the carriage and carriage-feeding mechanism, 60 the combination of type bars, and a device operable by one or more of the type bars for rendering the carriage-feeding mechanism inoperative, said device being mounted on a stationary part of the machine and the carriage-feeding mechanism being movable by 65
- the case-shift mechanism out of the field of operation of said device when the carriage is elevated.
6. In a typewriting machine having a platen carriage, an escapement, a horizontally movable escapement-operating tappet, and case-shift mechanism for moving said parts up and down in unison, the combination of means operable through the instrumentality of one or more of the individual type bar actions of the machine to shift said tappet out of coöoperative relation with the escapement, said tappet being moved out of coöoperative relation with said means when the carriage is in one of its case positions. 70
7. In a typewriting machine having character keys, type bars, an escapement device, and a tappet movable horizontally each time a character key is actuated to operate the escapement device, the combination of a vertically movable member adapted to shift the tappet out of coöoperative relation with the escapement device, and means operable by one or more of the type bars for actuating 75 said member.
8. In a typewriting machine having character keys, type bars, an escapement device, and a tappet movable horizontally each time a character key is actuated to operate the escapement device, the combination of a vertically movable member adapted to shift the tappet out of coöoperative relation with the escapement device, means operable by one or more of the type bars for actuating 80 said member, and a case-shift frame, said escapement device and tappet being movable relatively to said member by the shift frame to an upper case position in which the tappet is out of the field of action of said member. 85
9. In a typewriting machine, the combination of carriage-feeding mechanism, type bars, a rock shaft having a portion thereof located in the path of movement of one or more of the type bars and rotatable by the printing movement of said bar or bars, means operable by said shaft for rendering the carriage-feeding mechanism ineffective, and case-shift mechanism operatively connected to impart a relative movement between the rock-shaft-operated means and the carriage-feeding mechanism to move the same out of coöoperative relation. 90
10. In a typewriting machine, the combination of type bars, carriage-feeding mechanism, a rockable member adapted to be engaged and operated by one or more of the type bars, and means operable by said member for rendering the carriage-feeding mechanism inoperative. 100
11. In a typewriting machine, the combination of type bars, a rockable member located in the path of one or more of said type bars, and means operable by said member when the member is rocked by a type bar 105

for rendering the carriage-feeding mechanism inoperative, each type bar adapted to coöperate with said member being provided with a cam for rocking said member as the 5 type bar moves toward the printing point.

12. In a typewriting machine, the combination of a vibrating tappet support operable each time a character key is actuated, an escapement-operating tappet movable with 10 said support to operate an escapement and shiftable relatively thereto to an inoperative position, means for normally holding said tappet in an operative position, a cam device adapted to shift said tappet relatively 15 to the vibrating tappet support to an inoperative position, type bars, and means operatively connected to actuate said cam device located in the path of one or more of said type bars.

20 13. In a typewriting machine, the combination of a vibrating tappet support, a universal bar for vibrating said support, an escapement-operating tappet pivotally mounted on said support, means for 25 normally holding said tappet in operative position, a sliding cam device adapted to swing said tappet about its pivot to an inoperative position, type bars, and means located in the path of one or more of said type bars and 30 operable thereby to impart a sliding movement to said cam device.

14. In a typewriting machine, the combination of a vibrating tappet support, a universal bar for vibrating said support, 35 an escapement-operating tappet pivotally mounted on said support, means for normally holding said tappet in operative position, a sliding cam device adapted to swing said tappet about its pivot to an inoperative 40 position, type bars, and a rock shaft operatively connected to impart a sliding movement to said cam device and having a crank portion located in the path of one or more of said type bars.

45 15. In a typewriting machine, the combination of a vibrating tappet support operable each time a character key is actuated, an escapement-operating tappet movable with said support to operate an escapement 50 and shiftable relatively thereto to an inoperative position, means for normally holding said tappet in an operative position, a cam device adapted to shift said tappet relatively to the vibrating tappet support to an inoperative 55 position, type bars, means operatively connected to actuate said cam device located in the path of one or more of said type bars, and a case shift frame operatively connected to shift the tappet support relatively to said 60 cam device to move the tappet out of the field of action of the cam device in a certain position of the shift frame.

16. In a typewriting machine, the combination of a vibrating tappet support, a

universal bar for vibrating said support, 65 an escapement-operating tappet pivotally mounted on said support, means for normally holding said tappet in operative position, a sliding cam device adapted to swing said tappet about its pivot to an inoperative 70 position, type bars, a rock shaft operatively connected to impart a sliding movement to said cam device and having a crank portion located in the path of one or more of said type bars, and a case-shift frame operatively 75 connected to shift the tappet support relatively to said cam device and rock shaft to move the tappet out of the field of action of the cam device in a certain position of the shift frame. 80

17. In a typewriting machine, the combination of a vibrating tappet support, a universal bar for vibrating said support, an escapement-operating tappet pivotally mounted on said support, means for normally holding said tappet in operative position, 85 a sliding cam device adapted to swing said tappet about its pivot to an inoperative position, type bars, and a rock shaft operatively connected to impart a sliding 90 movement to said cam device and having a crank portion located in the path of one or more of said type bars, the type bars in alignment with the crank portion of the rock shaft being formed with cam portions adjacent their pivots adapted to engage the 95 crank portion of the shaft.

18. In a typewriting machine, the combination of an escapement device, a vibrating frame, an escapement operating tappet 100 pivotally held to the frame, a spring for normally holding said tappet in position to operate the escapement device when the frame is actuated, character key levers, type bars operable by the key levers, a universal 105 bar operable directly by said key levers and connected with the frame for vibrating said frame, and means operable by one of said type bars for swinging the tappet about its pivot to render the tappet ineffective on the 110 escapement device.

19. In a typewriting machine, the combination of an escapement device, a vibrating member, a universal bar for vibrating said member, character key levers, an escapement operating tappet pivotally held to said vibrating member to swing horizontally into and out of coöoperative relation 115 with the escapement device, and means operable by one of said key levers for positively swinging the tappet about its pivot independently of movement of the vibrating member by the universal bar to render the tappet ineffective on the escapement device. 120

20. In a typewriting machine, the combination of an escapement device, a vibrating member, an escapement operating tappet pivotally held to said member, means for 125

normally holding the tappet in position to actuate the escapement device when said member is vibrated, a slidably supported cam adapted to swing the tappet about its pivot to an ineffective position when said cam is moved in one direction, character 5 key levers, a universal bar for vibrating said member operable through the medium of

each of said key levers, and means operable through the medium of one of said key levers for actuating said slidably cam independent of movement of the universal bar.

This specification signed this thirteenth day of March, A. D. 1919.

ALONZO B. ELY.
